FIG. 4.

INVENTOR

JULIUS KOWALL

Beale & Park

ATTORNEY

UNITED STATES PATENT OFFICE.

JULIUS KOWALL, OF NEWARK, NEW JERSEY.

CUFF LINK.

Application filed March 16, 1921, Serial No. 452,657.

To all whom it may concern:

Be it known that I, JULIUS KOWALL, a citizen of the United States, residing at Newark, in the county of Essex and State 5 of New Jersey, have invented certain new and useful Improvements in Cuff Links; and I hereby declare that the following is a full, clear, and exact description thereof, reference being had to the accompanying 10 drawings, which form part of the specification.

My invention relates to cuff-links or cuff-buttons and has for one object connecting and binding together the ends of a cuff and 15 being adapted to present an attractive appearance.

To perform the above mentioned purpose I bend a rod of material, upon itself forming two loops and then bend the ends of the 20 material, respectively back upon themselves in a reverse bend forming two arms of equal length with the loops between said arm members said arms being adapted to pass through the holes of a cuff and to then elastically clamp together by means of knobbed 25 ends, and slight reciprocating reverse bends at the point of interlocking contact.

The cuff ends are thus pinched between the loops and respective arms member, each 30 cuff end being held in a three point suspension. One point on the arm member and the respective loops providing the other two points of contact.

In the open position the knobs are slightly 35 separated to admit of the arms passing freely through the cuff holes. When the arms are elastically engaged the knobs prevent the said arm members from disengaging.

40 In the accompanying drawings Fig. 1 is a side elevation showing my device engaged while connecting the ends of a cuff. Fig. 2 is a cross section of the cuff of Fig. 1 on the line 2—2, but showing my link as it appears 45 before clamping. Fig. 3 is a side view of my link disengaged. Fig. 4 is a cross section on the line 4—4 of Fig. 3.

Referring more particularly to the drawings AA denote the arm members of my cuff 50 link, *a* and *c* the loops formed intermediate

the arm members, *d* the bends in the arm members which rest against the edges of the cuff holes *c*, *c*. *D* denotes the balls or knobs surmounting the ends of the arm members, *b*—*b* represent the bends in the arms members at the point of interlocking contact of the arm members. *E* represents a conventional cuff.

In the drawings I have preferred to show my cuff link with two loops, the arm members extending rearwardly from the loops and then bending in reverse curves outwardly and continuing the bent until the arm members engage in front of the loops.

It is also evident that I can extend the 65 arms rearwardly and then continue bending in a like direction to form the arms as above mentioned.

It is also evident that the loops of my device keep the cuff separated or in other 70 words do not crush the natural even symmetrical bend of the conventional cuff.

It will also be seen from the drawings and description that my cuff link is formed of a pliable elastic material and in fact 75 forms a spring. The arms springing apart as soon as the ball members are disengaged.

Claims:

1. A cuff-link consisting of a bar member 80 twisted upon itself to form two loops intermediate two arm members said loops being adapted to separate the ends of a cuff and said arm members to pass through the holes of said ends and adapted to interlock each other beyond said ends, said arm members 85 being also respectively adapted to clamp respective end of the said cuff between said arm and said loops.

2. A cuff-link comprising an open spring member having ends of said spring member bent in reverse directions and provided with interlocking knobs or balls, two internally formed loops centrally placed in respect to the arm members forming a spring member and adapted to pinch a cuff between 95 said loop members and said arm members when the said knobs are interlocked.

In testimony that I claim the foregoing as my own, I affix my signature.

JULIUS KOWALL.
